COMBINED FORK AND KNIFE

Sam M. Baseel, St. Louis, Mo.

Application March 11, 1957, Serial No. 45,192

Term of patent 14 years

(Cl. D22—3)

FIG. 1.

FIG. 2.

FIG. 3.

Fig. 1 is an edge view of a combined fork and knife showing my new design;

Fig. 2 is a plan view; and

Fig. 3 is a side view thereof.

I claim:

The ornamental design for a combined fork and knife, substantially as shown.
